ATTORNEY

UNITED STATES PATENT OFFICE.

RICHARD A. HOFFMANN, OF ROSEBANK, NEW YORK.

TURNUBUCKLE LOCK.

Application filed October 29, 1919. Serial No. 334,257.

To all whom it may concern:

Be it known that I, RICHARD A. HOFFMANN, a citizen of the United States, and a resident of Rosebank, S. I., in the county of 5 Richmond and State of New York, have invented certain new and useful Improvements in Turnbuckle Locks, of which the following is a specification.

This invention relates to improvements in 10 turnbuckles or similar machine elements wherein a pair of aligned rods or stems, threaded right and left respectively, are screwed into a connecting member having the form of a slotted yoke, or being provided with a polygonal portion, for the application of a wrench or spanner.

A link of this sort is adapted for use wherever two opposite parts, to which the outer terminals of the rods are permanently 20 fixed, are to be held by tension in their adjusted position, as for instance in building and bridge structures, ship rigging, toggle joints, or similar contrivances requiring frequent adjustment on account of wear or 25 change of conditions.

It is however a well known fact that an ordinary turnbuckle does not keep its adjusted position very long, as the tensional strain of the rods will gradually turn the 30 buckle back, especially when the rods are attached to twisted strands which, together with everchanging wind stresses or constant vibrations, induce and facilitate a quick slackening of the turnbuckle from its tightened position. As this would undoubtedly weaken and endanger the whole structure 35 the importance of some reliable and handy locking device to prevent this incidental slackening of the buckle is self-evident.

One object of the invention therefore is 40 to provide a turnbuckle-lock system which, while based upon and restricted to the fundamental requirements of the problem, shall be comprehensive and elastic enough to be applicable to most different conditions and demands, yet will preserve and clearly exhibit its few typical elements in all its diversified shapes and constructions.

Another object is to make such system applicable to existing standard turnbuckles 45 without requiring any changes of their shape or expensive alterations.

A third object, harmonizing with the last named, is to contrive a system which can be represented by a self-contained and easily 55 detachable locking mechanism.

A fourth object is to provide a locking device which does not, on account of its mode of operation or construction, impair 60 the working strength of the turnbuckle.

A fifth object is to provide means for instantly locking or releasing the turnbuckle by a simple manipulation without the use 65 of tools or detaching any separate parts like cotter pins, locknuts, loose keys, wires or the like.

A sixth object is to provide a positive lock 70 which will operate at practically any desired point of the adjustable length of the turnbuckle.

A seventh object is to provide means whereby the turnbuckle is locked automatically when the thread begins to slacken, in case the previous manual locking has been 75 carelessly executed or not fully accomplished.

An eighth object is simplicity and low cost of manufacture, together with strength and durability of construction.

These various objects are attained by a 80 coherent system whose scientific principles will be set forth hereafter and which is illustrated in some of its possible phases and combinations by the novel devices and mechanisms herein described and shown in the 85 accompanying drawings, in which:—

Figure 1 is an assembled view showing two turnbuckle-locks with automatic engagement, designed in accordance with the invention and applied to a turnbuckle of the 90 larger size and of such design and proportions as are accepted by most American manufacturers as "standard." The turnbuckle-lock to the right is shown in a cocked position, that is, ready to close automatically.

Figure 2 is a sectional view on line 2—2 of Figure 1.

Figure 3 is a sectional view on line 3—3 of Figure 2 showing the support of the automatic engagement device.

Figure 4 is a sectional view on line 4—4 of Figure 2 showing the locking device proper.

Figure 5 is a sectional view on line 5—5 of Figure 2, illustrating the starlock-frame.

Figure 6 shows a detail, in perspective, of the skid which supports the lock.

5 Figure 7 is a perspective view of this lock.

Figure 8 is a detail view of the starlock-frame.

10 Figure 9 is a sectional view on line 9—9 of Figure 8.

Figure 10 is a detail view of the plate shown in Figure 3 which supports the automatic engagement spring.

15 Figure 11 shows how the inner terminals of the threaded rods are shaped to form the "key" which the system requires.

Figure 12 shows an end view of this key.

Figure 13 is a side-view showing a simplification of the device displayed in Figures 1 and 2, waiving the advantage that the automatic engagement and the provision for adjusting the starlock-plate by shimplates afford. The turnbuckle is indicated by dotted lines only.

20 Figure 14 is a view of the outer end of the device.

Figure 15 is a view of the inner end of the device.

Figure 16 shows a turnbuckle starlock 30 with its lock engaging the outside thread of the bolt. Starlock-plate and locking device form one single plate.

Figure 17 is a side view of this device.

Figure 18 shows an inner end view of it.

35 Figure 19 is a sectional view taken on line 19—19 of Figure 16.

Figure 20 is a sectional view taken on line 20—20 of Figure 16.

40 Figure 21 shows a development of the plate which when bent as shown in Figures 16 and 17 forms the device illustrated.

Figure 22 represents a similar arrangement manufactured from one single wire.

Figure 23 is a front end view of this lock.

45 Figure 24 is a rear end view of the same.

Figures 25 to 30 are diagrams to be consulted in connection with the theory of leading principles of the system which is about to be propounded.

50 Other applications of the system, especially its modification for finer threads, such as for instance are used for airplane bracing, are shown and described in separate applications for Letters Patent.

55 Referring now in particular to the fourth object of this invention, it is obvious that any interruption of the thread by any holes, grooves, or the like, either longitudinal or crossways, would weaken the tensional 60 strength of the rods and the smooth action of the thread. The application of side pressure upon it for the purpose of locking would likewise be undesirable and injurious to the thread, besides being unreliable.

65 There is however one single point in a

turnbuckle which never comes under tensile stress, this is the extreme and idle portion of the inner terminal which consequently is the proper place for making the unavoidable inroad upon the material, or 70 addition to it, as the case may be. This latter is preferred and accomplished by giving the terminal such a section that an inner surrounding stationary part can take some grip upon it, forming thereby a male 75 and female combination.

While the surrounding part must be stationary in relation to the rotary motion of the thread, it must be movable in an axial direction for the purpose of easily engaging 80 or disengaging the rod. This is best accomplished by utilizing the slot usually provided in a common turnbuckle as a slide for the plate or frame forming this other half of the male and female combination 85 (see Figures 1 and 5), or providing a separate slot for such purposes. The frame itself can, in addition, be formed with side flanges 4 and 5 (Figures 8 and 9), to increase the bearing surface and to secure its 90 position and guidance at right angles to the turnbuckle axis.

Regarding the male and female combination it is obvious, if the male member or "key" is closely and uninterruptedly surrounded by the female member or "keyway," if for example it consists of a key of square cross section fitting into a square hole, that it permits an adjustment of the 95 thread at quarter turns only; but if now the surrounding hole is formed by a zigzag polygon following the outline of a combination figure, which results or may be derived from repeating the key section as a geometrical unit at equal pitch angles, say eight 100 or twelve to the circle, or at 45 or 30 degrees respectively, the number of possible adjustments is multiplied in proportion. The keyway in the female member thereby assumes the shape of a figure, commonly 105 called a "star," and from this feature, which is retained in every variation and application of the invention, I have ventured to call this system the "Turnbuckle starlock 110 system."

115 The advantages of this improvement are threefold.

First, the sixth object of the invention is thereby attained. Taking for example a standard of 10 threads per inch for a $\frac{3}{4}$ turnbuckle, a key of square section fitting into a zigzag polygon of 12 radiating points (see Fig. 25) allows a locking adjustment at every 120th of an inch, which is more than sufficient for all practical purposes. 120 With smaller size turnbuckles the conditions are even more favorable. Assuming for instance, a turnbuckle for a $\frac{3}{16}$ screw having a standard pitch of 24 threads per inch, a 125 triangular key fitting into a starlock of only 130

six outer points, as shown in Figure 27, brings the minimum variation of adjustable length to $1\frac{1}{44}$ of an inch, and as will be pointed out afterwards, the possible slip or loss in tension, if the locking is left to the automatic engagement, will in the majority of cases be less than half of this amount.

The second advantage lies in the facility of manufacture. It is easier to cut or punch with a die a polygon or star out of a plate than it would be to shape or file the key into a prismatic body having the same number of angular protrusions. The form of the key by representing in its cross-section a geometrical unit only of the keyway, is therefore simplified.

The best evidence of the third advantage is given by the following consideration. The triangular key, shown in Figure 27, can engage with the hexagonal star at partial turns of 60 degrees. Theoretically this same result could be obtained by giving the key a cross-section of a simple hexagon fitting into a hexagonal hole, but in that case the angles would be obtuse instead of being acute whereby the hold of the female member upon the male is diminished, and the danger of slipping becomes imminent with increasing pressure or wear.

Regarding the geometrical form of the cross-section of the key and the corresponding keyway there is this much to note:—

First:—The outline of the geometrical unit is confined and limited by the body circle or depth of thread of the rod.

Second:—Any shape of cross-section which, when repeated at equal fractions of 360 degrees around the axis of the rod, will indicate a uniform star in one complete revolution, is adapted to serve as keyform and as a unit for the starlock.

Third:—A "star" in this case is understood to be a closed, uncrossed line, consisting of equal and uniform broken or curved components describing a distinctly reciprocating course around and in relation to a common point, the center of the star. The reciprocation consists in a periodic variation of the radial distances, while the direction of the course is tangential to one or more base circles concentric to the star center.

This implies that unless the theoretical form is for practical reasons shortened or incompletely executed the figure used as a unit, when rotated in a plane about an axial point must prove congruent to itself in at least one more position than the initial one, furthermore, that the axial point and the center of the star described is coincident with the center of gravity of the figure, and that from this center the unit, as well as the star, can be divided by one or more lines into congruent parts.

These corollaries however, while applying

to every case, are not in themselves sufficient to supersede the above given definitions and to describe the geometrical properties of a unit, because the area of a circle for instance, turning in a plane about its center of gravity, is congruent to itself at any angle and can be divided into congruent parts, without describing or suggesting a reciprocating course towards or from this center.

Neither are equal angles or symmetry indispensable or have sufficient characteristics to answer the purpose, as an examination of Figures 28 and 29 will show.

To make the requirements still clearer, let us compare the unit of Figure 29 with that shown in Figure 30. Although this latter figure, a crescent, is isogonal (120—120), has an axis of symmetry 121—121 and its center of gravity may also coincide with the axis of rotation 122, it is evidently not fit to be used for a unit, because after half a revolution (119^{a-b}) it will not be congruent to its first position, nor can it be divided into parts, congruent in the same plane (that is without reversing them) and will therefore not describe a uniform star.

Figure 29 however answers the definitions although it is not symmetrical on line 121^a—121^a which divides it into congruent halves. Figures 25, 26, 27 and 28 also show possible combinations, the units indicated by numerals 116, 123, 125, 127 and the stars by 117, 124, 126 and 128 respectively.

Practice of course will confine itself to a few simple preferred combinations.

When the starlock plate engages the key some means must be provided to lock or fasten it in this position.

Also when the starlock plate is disengaged, and the turnbuckle is being readjusted, the plate has to be temporarily arrested in an out-of-the-way point to run clear of the key.

As outlined by the fifth object of the invention the main requirement for this proposition is a device which affords an instantaneous grip and likewise a release that can be effected by hand on nondetachable parts.

In other words, expressing it in purely technical terms, the resisting force which is used to check the movement of the starlock-plate in the axial direction of the turnbuckle temporarily or as long as desired, must be the result of a dynamic rather than a static arrangement. To illustrate the difference: A cotter pin inserted through the end of the key behind the starlock-plate, or a collar or nut to prevent its dislocation, would be a "static" device, depending upon the presence and passive impermeability of the material only. A connection however between the starlock-plate and the turnbuckle, that comprises also the active inter-

ference of energy inherent in the device, for instance the resiliency of a spring, gravity or some other kinetic force which in turn is exposed to and yields to manual counteraction along its line of action, would be a dynamic device.

The principal point in this case is not that the integral energy of this connection should be used to hold the male and female members together—which may be the case and is not objectionable, but in view of the purpose expressly stated in the fifth object, the main point is that the connection should comprise a member whose energy must be actuated by manual checking or releasing to complete the closing or opening operation.

It is a matter of option and circumstances how many intermediate links are to be used in this connection between the starlock-plate, 20 and the point of support on the turnbuckle, and, as will be shown, will vary according to whether the point of support is taken on the inside or the outside part of the threaded bolt.

25 The point of application also can vary according to practical requirement. In large turnbuckles, for example, the thread of the rod can safely be used as a hold for the lock, either on the inside of the turnbuckle (see Figure 2) or outside of it (see Figures 17 and 22); with smaller threads this hold would be too precarious besides ruining the helix, and the hold must be confined to the turnbuckle itself as is shown 35 in a separate contemporaneous application for Letters Patent, referred to above.

There are then three fundamental elements in the starlock-system.

1. The key
2. The starlock-frame (or keyway)
3. The dynamic lock.

No other parts or elements are necessary to make the system operative, and the fourth part, the "automatic engagement," which 45 will be spoken of presently, is only an optional addition and modification of the third element to make it more convenient and safeguard its working.

The function of this part is outlined in 50 the statement of the seventh object and is preferably supplied by a compressive coil spring.

After stating thus broadly the scientific principles and extant features of the system 55 it remains to describe some of the applications and elaborations of details as shown by the accompanying designs.

Figures 1 to 12 illustrate the device applied to a commercial standard turnbuckle. 60 The only change to be made concerns the inner terminals of the rods which are filed or otherwise formed into squares 1 as Figures 11 and 12 shows. The front edges 1^a can in this case, as well as in all following 65 cases, be rounded off or the whole key be

given a slight taper to facilitate the entrance into the starlock-plate. This plate 2, Figure 8, which is shown here perforated by an eight pointed star 3, is preferably made of hardtempered steel and provided 70 with four ramified extensions 4, bent at right angles into clips 5 which serve as sliding flanges (Figure 9). The locking device consists in this case of two plates and a flat compression spring (see Figs. 6 and 75 7). Figure 6 shows the first plate 6, which, when cut or punched and bent into the shape shown, serves as support for the locking plate proper 7, and also for the fourth part, the automatic engagement, referred to 80 later.

As can easily be inferred from the drawing the narrow middle part 8 of the plate when developed has a circular aperture 9 fitting around the threaded rod 10, Figures 85 1 and 2, with sufficient clearance when assembled. The plate widening out above and below this narrow part to the full width of the slotted surface 11—11 of the turnbuckle is then doubled up, 12^a and 12^b, the doubled 90 up portions are clamped together by clips 13, branching from and integral with the plate 6. Then the remaining portions of the plate are bent at right angles to form parallel skids to slide on the slotted surfaces 95 11—11, the distance between them corresponding to the height 20 of the yoke.

Parallel with and in proximity to these upper and lower bends are cut two slots 21^a and 21^b for inserting and guiding the locking plate 7. This plate is an elongated frame whose width corresponds to the middle part 8 of the support, determined by the width 22, Fig. 1, of the turnbuckle slot, proper clearance being allowed. 100

The upper edge 23 of this plate is bent at right angles towards the center of the turnbuckle and forms a bifurcated stop 24—24 which, when the plate is pressed down, disengaging the rod, makes contact with the 110 top edge of the starlock-plate 2, provided that the latter happens to be underneath it, and thereby prevents the upper edge of the oval aperture 28 from interfering with the top of the thread. 115

The part 25 between the two prongs 24—24 is doubled under to form a clamp which grips the compression spring 26.

This latter has the form of a bow or an arch whose abutments 27 rest on the upper 120 skid extension of plate 6, as shown best in Figure 4.

In the middle portion the plate 7 has an oval hole 28 whose lower edge 30, normal to the long axis of the ellipse, is the proper operative point of the locking device and is adapted to take a grip on the rod by catching between any adjoining turns of the thread. 125

To make this biting portion of the plate 130

conform to the pitch or ascending curvature of the thread the sides 31-32 are given a little twist around the longitudinal axis of the elliptical aperture, to the right or left, 5 as the pitch of the bolt thread may call for, but the portion below the edge 30 is rebent into the plane of the top part of the locking plate.

After the plate 7 is assembled, by inserting it through the slots 21^a and 21^b, the foot 10 33, being straight as yet, is bent backwards to hook over the doubled up part 12^b of the plate 6, as shown best in Figures 2 and 4.

The skid portions of the plate 6 are when 15 developed, wider than the width of the slotted surface 11-11 and are parted by incisions or cutouts in such a way that the outside parts 34^a and 34^b can be bent to form gliding channels for the extensions 4 and 5 20 of the starlock-plate 2 (Fig. 8), which is made to ride on the center guides 35^a and 35^b that pass through the slots 36^a and 36^b in the starlock-plate provided for this purpose.

For assembling the mechanism the support or skid plate 6, bent into shape as 25 shown, is first inserted into the slot 22 (Fig. 1), holding the middle part in an axial direction, then the plate is canted into a lateral direction, the locking plate with the 30 spring in place (Figure 7) is inserted through slots 21^a and 21^b, and the lower end 33 is bent over the part 12^b with working clearance. Then the starlock plate 2 is mounted over the center guides 35^a and 35^b.

It is to be observed here that the sides of 35 the starlock-plate 2 in this arrangement are not made to closely fit either the channels 34^a and 34^b or the yoke slot 22 but have a liberal clearance which is now to be made up by "shimplates" or fillers 34^c and 34^d, (Figure 5) of brass or other suitable material. This gives facility for properly adjusting the starlock in case that the threaded outlets of the turnbuckle happen to be improperly centered in regard to the yoke 40 11-11 and also lessens the friction of the extensions 4 and 5 in the channels 34^a and 34^b. The outer shimplates 34^d are safeguarded against dropping out by dog's earing, that is, turning the hind corners 34^c (Fig. 6) partly over the shimplates (see also Fig. 1). The latter shimplates are superimposed edgewise upon the closefitting surface shimplates 34^c and keep these from coming out.

To the assembly is then added the compression coil spring 37 which represents the automatic engagement and must have length 45 and resiliency enough to protrude a short distance beyond the rear end of the channels 34^a and 34^b, when pushing the starlock-plate and the spring fully up to the front without materially compressing the latter. Its outer diameter corresponds to the available space 50 between the yoke arms 11-11 and the center

guides 35^a and 35^b, clearance provided, and 70 its strength must be but moderate, as its function does not call for great force, working at practically right angles to the torsional stress of the rod.

Finally the assembly is completed by 75 stripping the rear plate 38, (Fig. 10) with its slotted ears 38^a over the clips 38^a of the channels 34^a and 34^b, while the clips 38^c pass through the slots 38^c. These clips which hitherto extend straight from the 80 ends of the channels are now, after passing through the slots 38^a and 38^c bent over (as already indicated in Fig. 6), securing the rear plate 38 and confining the spring 37 into the available inside space. 85

In cases where the outer terminals 39 are connected to shackles 40 so that both can turn easily and independently, two locking devices as shown, are required, one for each rod, but where there is no relative 90 rotation of the rods to each other and only the turnbuckle can revolve, one locking device only is necessary.

The mode of operation is as follows:—

When both locks are disengaged and removed from the keys towards the middle of the yoke they will leave between them sufficient space to insert a bar or similar implement for adjusting the turnbuckle. 95

When this is drawn sufficiently tight, the turnbuckle locks are seized one at a time or both at once, and the lock plate is pressed down at 23, so that the prongs 24 will touch the upper edge of the starlock-plate, care being taken that in seizing the bottom of 100 the skid, shown in Fig. 6, the end 33 of the plate 6 is not interfered with. Then the locks are pushed over the keys as far as possible with a moderate compression of 105 the spring 37, and the hand pressure on 23 is then released. The lower edge 30 now catches on the thread, fastening the device 110 on the rod.

The keys 1 meanwhile may or may not have entered the starlock-frames as can 115 plainly be seen. If not, the locks show a position like the one on the right sides of Figs. 1 and 2. The starlock plates press simply against the ends of the keys. By now striking the bar a gentle tap or jar a 120 click may be heard, and the starlock plates will be observed to slide over the keys. If one tap is not sufficient to close both ends, a second tap will complete the locking.

But even without this final operation the 125 turnbuckle is safeguarded already against unscrewing; as long as the locking plate 7 takes a sufficiently far reaching bite on the rod to compress the spring 37 somewhat, leaving the automatic engagement in a 130 cocked position.

For when the thread begins to slacken spontaneously, the key will have to enter the starlock plate as soon as it turns into

the next locking position. The loss thus sustained in tension is negligible and, as aforesaid, at the most will be less than the minimum variation in adjustable length.

5 The unlocking of the turnbuckle is done by pressing the prongs 24 down upon the top of the starlock plate and simply sliding the device back to the middle part of the yoke.

10 It will be obvious that the dynamic locking device in this case consists in a series or chain of members bringing the starlock plate into a rigid connection with the thread of the bolt.

15 These intermediate members are successively the lock plate 7, the spring 26, the support 6, the rear plate 38 and the coil spring 37. Two of these members possess elastic force, and the manual release or the 20 suspension of these forces is necessary to complete locking or unlocking. It is also clear that the fourth part, the automatic engagement, is not an independent element, but consists simply in the elasticity of the 25 last member of this locking chain, where it connects to the starlock plate.

This application of the starlock system exhibits all essential features of it clearly and most elaborately. Nevertheless the 30 device consists only of four punched out plates and two springs, joined together without a single rivet, bolt or screw.

35 There will now be finally considered what changes and simplifications the system allows in cases where the advantage that the addition of the automatic engagement affords is dispensed with.

40 The elimination of the coil spring 37, which, as was shown above, is not an essential and indispensable feature, but is added mainly for the sake of greater efficiency, implies also the omission of the parts supporting it (plates 6 and 38). The remaining parts 7 and 2 have to be slightly altered to 45 form a selfcontained mechanism. What then remains of the device is shown by Figures 13, 14, and 15.

45 On the starlock-plate the sliding flanges 4 and 5 and the slots 36^a and 36^b are omitted. 50 Instead its top and bottom parts are bent over in the form of brackets 90 and 91. Both brackets contain the slots, formerly shown at 21^a and 21^b, Fig. 6 and indicated in Fig. 13 by numerals 92^a and 92^b only. The 55 brackets extend the whole width of the slotted yoke and supersede the sliding flanges 4 and 5. The upper bracket has in addition the upturned flanges 93^a and 93^b which confine the spring 26 in its place. 60 The lower edge 33^a of the locking plate 17 is turned forwards instead of backwards to form the lower stop, and the prongs 24^a of the upper flange 23^a are bent downwards to form the upper stops, both kinds of stops 65 to operate on the side brackets 90 and 91

respectively of the starlock-plate. Otherwise the construction is identical with the original device.

In such cases where the range provided for adjustment is only short, and consequently the extra length of thread showing outside the buckle does not afford much space, this form of the invention will be the most economical and least expensive, reducing it to the smallest available space; if however enough play can be provided on the outside part of the threaded bolt, as shown in Figure 17, a still more simplified embodiment of the principles of the invention is possible by transferring the grip upon the 75 thread from the inside of the buckle to the outside, as anticipated already in the conception of the theory.

In that case one can dispense with the 80 spring 26 whose function, that is:—to form a resilient union between the starlock plate 2 and the locking plate 17, can be transferred to these two parts by uniting them 85 into one resilient plate (see Figures 16 to 21).

90 That the locking plate thereby doubles, gripping the thread on the bottom (99^a) as well as on the top (99^b) is due to the necessity of providing a gap, opened and closed 95 by the resiliency of the spring, similar to the gap between 92^b and 33^a, shown in Fig. 13. Otherwise this plate is formed and acts on the same principles as before, though its three constituents 2, 26 and 17 are now combined in one single plate of spring steel, 100 shown before a bending in Figure 21.

105 The recesses 94^a and 94^b serve as guides and supports for the middle part containing the starlock 3. The inner rims of the locking eyelets 99^a and 99^b are interrupted by the lips 95 and 96, cut or punched out as shown. These lips are to be curled to form halfround stops indicated by 95^a and 96^a Fig. 17, which glide over the threads without danger of gripping or injuring them 110 when the lock is disengaged. This is done by pressing the upper and lower arms 98^a and 98^b together and pulling the middle portion of the plate off the key. As soon as the 115 key becomes disengaged the arms are freed, then the catches 99^a and 99^b which are formed and pitched analogous to former locking edges take hold again of the thread. But while arresting the plate they will permit the rod to be turned and to advance 120 freely between them until the key again reaches the starlock.

125 If the turning of the rod is continued, the spring will incidentally transform itself into an automatic engagement, that is, the spring will yield enough to develop a moderate tension on the part containing the starlock, and as soon as the position of the key permits, it will slip over the edge and lock the key. If this is not desired then and 130

there some additional leeway must be given to the rod by slipping the catch a little nearer to the buckle.

As for the shape of the plate shown in Figure 21 it may not be amiss to point out that it ought not to be symmetrical, one arm being somewhat longer than the other, as a comparison with Figure 17 will disclose.

Figure 22 finally illustrates the execution of this same device, identical in principles and general arrangement, by means of a single continuous wire. It therefore introduces no new element of construction, as in fact none of the two last devices does, but they merely represent the gradual and ultimate skeletonizing, so to speak, of the original scheme, just as circumstances may permit.

The wire starts at 100, Figure 24, is wound into a coil 101, then forms the upper catch loop 102^a, 110^a, 102^b (see Figs. 22 and 23), is then wound into a coil 103, thereupon outlines the starlock-keyway 104, which is in this case based upon a rectangular key as a unit, but may as well present some other suitable form, then it forms the coil 105 and the lower catch loop 106^a, 110^b, 106^b, after which it is wound into a coil 107 and closes the circuit by the hook 108 which, together with 100, is held fast by the loop 109 formed by the starlock 104.

It will be seen that the originally weak resiliency of the locking arms is greatly increased by the coils 101, 103, 105 and 107 also that the starlock-portion, confined in the slot by the yoke and the coils forms a very substantial frame and is well suited to supersede a solid plate. It may also be remembered that the biting portion of the catch loops 110^a and 110^b must follow the pitch of the thread, may this be a right- or left-handed one. Also that in order to get a maximum range of adjustment the length of the locking arms must approximately correspond to the length of thread available or presumably required, as Figure 17 shows best.

Thus it will be seen that the starlock-system in logical consequence leads up to very simple and inexpensive forms and affords a variety of applications, which was the goal of the first object of this invention.

Other forms and modifications are possible along the lines indicated, and it is therefore understood that the invention is not to be confined to the exact description and showing presented but rather to the claims hereto appended.

I claim:

1. In a turnbuckle, comprising a slotted buckle and one or two rods threaded into the buckle, the combination with a perforated frame sliding in the slotted portion of said buckle and forming a male and female locking union with the inner end

of the threaded rod, whose end section is of such particular shape that when rotated it will fit at different angles into the contour of the frame perforation; of a gripping device supported by said frame and acting upon said threaded rod, and a spring, cooperating with the gripping device in such manner that it normally effects the grip of said device upon the threaded turnbuckle rod, while its actuation releases the gripping engagement. 70 75

2. The combination with a turnbuckle, consisting of a buckle and one or two rods threaded into the buckle; of a support slidably engaged with the buckle, a sliding frame, guided by and movable on the support, said frame being provided with a star-shaped opening, representing a keyway, a key formed on one of the inner ends of the threaded rods, representing a star-unit, substantially as defined, a gripping device mounted on said support and adapted to engage the thread of said rod, a spring cooperating with the gripping device for actuating said engagement, and means to 80 85 interlock the keyway with the key when the gripping device has engaged the threaded rod. 90

3. In a turnbuckle, a slotted member, one or two rods threaded into this member, a plate, mounted at right angles to the axis of rotation, slidably engaged with the slotted portion of said member and having a star-shaped opening concentric with the axis of the threaded rods, a key formed on the inner end of one of these rods, having such sectional area that it can engage with said star-shaped opening to lock the rod against rotation, a perforated frame adapted to surround the thread of the keyed rod in such manner that it can take an engaging grip upon the thread, a spring device resting on supports integral with and extending from the aforesaid plate, means to connect this spring device operatively with said gripping frame, and means to limit the engaging and disengaging movements of the spring-actuated frame. 100 105 110

4. In a turnbuckle, a slotted member, one or two rods threaded in alignment into this member, a skid-like support guided by the slotted member, a plate mounted at right angles to the turnbuckle axis, adapted to move in an axial direction in connection with said support and provided with a star-shaped opening, a key integral with and formed on the inner end of one turnbuckle rod, said key adapted to engage with the star-shaped opening in the aforesaid plate to lock the rod against rotation, a frame, movably mounted on the skid-like support and adapted to take an engaging grip upon the rod, a spring device actuating the gripping movement of said frame, a limit stop connected with said frame, and means to auto- 115 120 125 130 135

- matically engage the star-shaped opening in the plate with the key, as soon as the key turns into a position registering with the contour of the star-shaped opening.
5. The combination with a turnbuckle, comprising a slotted member and one or two rods threaded into this member; of a skid-like support guided by the slotted member, a plate adjustably mounted on the support, independently movable in an axial direction, and provided with a star-shaped opening, a key integral with and formed on the inner end of one turnbuckle rod, said key being adapted to enter into a locking engagement with said star-shaped opening in the aforesaid plate, a frame adapted to engage the thread of the rod, a spring mounted on the support and forming a resilient seat for this frame, two limit stops to regulate the movements of said frame, and a coil spring sustained and guided by the skid-like support in such a manner that it will force the plate with the star-shaped opening over the key as soon as the relative position of these two parts will permit it.
6. The combination with a turnbuckle, comprising a buckle and one or two rods threaded into the buckle; of a key, integral with and formed on the inner end of one of the rods, of two plates and a spring forming a self-contained separate locking device, slidably engaged with the turnbuckle, the first plate being provided with a cutout fitting at a multiplicity of angles on the said key, the second plate provided with a cutout adapted to take a locking grip on the turnbuckle rod, and the spring forming an operative connection between the two plates.

7. The combination with a turnbuckle, comprising a buckle and one or two rods threaded into the buckle; of a key formed on the inner end of one of the rods, and of four plates and two springs, forming a self-contained separate locking device, the first plate bent into a skid-like main support, slidably engaged with the turnbuckle and adapted to guide and sustain the other plates and springs, the second plate provided with a cutout adapted to take a locking grip on the turnbuckle rod when actuated by the first spring, the third plate provided with a cutout fitting at a multiplicity of angles on the said key, and adapted to engage with said key when actuated by the second spring, and the fourth plate forming a support for the second spring; the springs serving as operative connections between the plates and for the purpose set forth.

8. The combination with a turnbuckle, comprising a slotted buckle and one or two rods threaded into the buckle; of a key formed on the inner end of one of the rods, a separate locking element, slidably engaged with the buckle, said element having an aperture forming a keyway which fits at a multiplicity of angles on the key, and being provided with an elastic part, integral with said element, and adapted to take a gripping hold on said keyed rod, and of means to operatively engage and disengage the locking element with the rod, substantially as shown and for the purpose set forth.

In testimony whereof I have signed my name to this specification.

RICHARD A. HOFFMANN.
